UNITED STATES PATENT OFFICE.

ROLAND R. CRUM, OF WHITTIER, CALIFORNIA.

CORE DRILL.

Application filed August 12, 1922. Serial No. 581,431.

To all whom it may concern:

Be it known that I, ROLAND R. CRUM, a citizen of the United States, residing at Whittier, in the county of Los Angeles and State of California, have invented a new and useful Core Drill, of which the following is a specification.

This invention relates to an improved rotary core drill, particularly of the type by which a sample core is formed and extracted to determine the character of formation encountered.

An object of the invention is to provide a core drill in which the core receiving barrel and the core bit are removable as a unit.

A further object is to provide a core drill in which the water displaced from the core receiving barrel by the core, is directed downwardly along the outer surface of said barrel to maintain the core barrel at a temperature which will eliminate a burning of the core by the friction of the rotating barrel against the stationary core.

Another object is to provide a core drill in which the circulation water is prevented from passing directly into the upper end of the core barrel; and to provide a drill in which the water displaced from the core receiving barrel is kept separate from the circulation water and discharged directly into the drill bore.

Another object is to provide a core drill having a central core receiving barrel, a discharge chamber surrounding the barrel, and a circulation chamber surrounding the discharge chamber, the discharge chamber being closed to communication with the circulation chamber and communicating directly with the drill bore, whereby water displaced from the core barrel by the core is directed into one end of the discharge chamber and is discharged from the other end of said discharge chamber directly into the drill bore, independently of the circulation water.

A further object is to provide a core drill having a core receiving barrel provided with valve means at its upper end to permit an exit of water displaced by the core, there being a discharge chamber communicating directly with the drill bore and enclosing the barrel and valve means, whereby the valve is not subjected to the pressure of the circulation water.

Another object resides in the provision of an improved form of outer boring bits.

In withdrawing the drill and the core barrel there is a tendency to produce a suction at the lower end of the core barrel which sometimes operates to withdraw the core so that it becomes lost. One of the objects of this invention is to provide means for preventing the loss of the core in this way.

Various other objects and advantages will be more fully apparent from the following description of the accompanying drawings, which form a part of this disclosure, and which illustrate a preferred form of embodiment of the invention.

Of the drawings:

Figure 1 is an elevation of my improved core drill.

Fig. 2 is a bottom plan view.

Fig. 3 is an enlarged vertical section.

Fig. 4 is a plan section on line 4—4 of Fig. 3.

Fig. 5 is a detail elevation of cutter supporting body member.

Fig. 6 is a section on line 6—6 of Fig. 5, looking upwards.

Fig. 7 is a perspective view of the cutter supporting body member and the elements carried thereby, removed from the main body member.

Fig. 8 is a perspective view of one of the outer boring cutters.

Fig. 9 is a vertical section of the lower portion of the drill, in operating position in a drill bore, and

Fig. 10 is a detail view of a modified form of core bit construction.

In prospecting mineral fields core drills are often employed for the purpose of obtaining samples of underground formations, and in drilling wells, particularly oil wells, it is often desirable to obtain samples of the formation for the purpose of obtaining a record of the various strata encountered, and in providing a core drill for these purposes which will successfully function in the various types of formation, certain requirements must be rigidly adhered to. As a drill of this character is ordinarily operated in the presence of circulating flushing water which carries the cuttings to the surface, it will be evident that the core, especially when operating in soft or sand formations must be effectively protected against the flushing action of the water, and further as the rotative action of the drill against the stationary core is productive of friction

which has a tendency to burn the core it is important that provisions be made for cooling the core.

In a great number of core drills heretofore proposed, the upper end of the core receiving barrel is in communication at times with the water circulating passages, and the core is subjected to the full pressure of such water. This, I have found to be of considerable detriment to speedy operation and to the obtaining of perfect cores, therefore, in the present invention I provide means for preventing direct communication between the circulating chamber and the end of the core barrel, and furthermore the core barrel and core barrel discharge is entirely independent of the water circulating system.

Referring to the drawings, the body of the drill consists of a main tubular body member 1 attached to the drill string, and providing a water circulation chamber 2, and a lower cutter supporting member 3 screw-threaded into the lower end of the member 1. I provide means for preventing communication between the circulation chamber and the upper end of the core barrel. For this purpose the member 3 carries a tubular member 4 projecting upwardly into the chamber 2 of the body and providing a discharge chamber 5 which is closed at its upper end and has no communication with the chamber 2.

A core barrel 6 has a screw-threaded engagement into the lower end of the body member 3 and extends upwardly into the chamber 5, the bore of the body member 3 throughout a major portion of its length being slightly larger than the exterior diameter of the core barrel 6, so as to provide a restricted extension 7 of the discharge chamber 5. When the drill is pulled upwardly there is a tendency to produce a partial vacuum in the core barrel 6 which might pull out the core. In order to prevent this I provide means for balancing the partial vacuum, that is to say, I provide a construction whereby a partial vacuum will be formed in the chamber 5 as well as within the core barrel. For this purpose I provide the body member 3 with discharge ports 8 communicating with said chamber extension 7 and discharging fluid from the chamber 5 directly into the drill bore. These discharge ports preferably incline downwardly (see Figure 3) as this direction increases the effect in forming the partial vacuum in the extension 7 which communicates with the discharge chamber 5. These ports therefore perform two functions.

The upper end of the core barrel 6 carries a plug member 9 having ports 10 and a closure in the form of a disc 11 slidable on a headed stem 12 fixed in the plug member, normally closes the ports 10 under the influence of a spring 13.

The valve 11 sits directly on the end of the barrel and the space around its edge is not obstructed in any way, and hence if the valve disc is off its seat at all, it will operate to open communication between the chamber space 5 and the interior of the core barrel.

The lower extension 14 of the core barrel carries a tubular core bit 15 whose bore registers with the bore of the core barrel, the lower edge of said bit being provided with radially disposed cutting teeth 16.

The body member 3 is provided with two opposed outer boring cutters 17, the member 3 being cut away, as at 18, to provide clearance for the cuttings and for the action of the flushing water, and recessed as at 19 to receive the shanks of the cutters 17.

The cutters 17 have horizontal dove-tail webs or tongues 20 and the member 3 has corresponding dove-tail ways 21 whereby the cutters may be laterally slid into place, each cutter being rigidly secured by a bolt 22 extending through a bore 23 in the body member 3 and screw-threaded into the cutter shank.

The cutters 17 are oppositely angled relative to the vertical and extend below the lower surface of the member 3 with their cutting edges angled outwardly and backwardly relative to the direction of rotation so as to urge the cuttings towards the outer periphery of the drill, each of said cutters 17 and each of the teeth 16 of the core bit 15 being provided with proper relief rearwardly of their cutting edges to produce an efficient cutting action.

Extending downwardly from the upper surface of the member 3 are circulation ducts 24 which terminate adjacent the shanks of the respective cutters 17 and direct the flushing water along the forward faces of said cutters.

In Figure 10 of the drawings, I have illustrated a modified form of structure in which the core bit 15^a is screw-threaded directly into the lower end of the body member 3, and the core barrel 6^a is screw-threaded directly into the upper end of the core bit. This structure may be conveniently used in instances where it is not desirable to have the core bit extend much beyond the lower ends of the outer boring cutters.

In the operation of the drill, the core 25 displaces the water within the core barrel 6, such water forcing open the core barrel valve 11 and flowing into the discharge chamber 5 from which it discharges through the ports 8 into the drill bore. As the chamber 5 and extension 7 thereof surround the core barrel throughout nearly its full length it will be evident that in such an arrangement an effective means has been provided for cooling the core barrel so as to eliminate any danger of burning the core. Further it

will be plain that, with the core barrel entirely enclosed within the tubular member 4 which has no communication with the circulation chamber 2, the core barrel 6 and its 5 valve 11, and the core, when the valve 11 is opened, are not subjected to the pressure of the circulation water and for this reason the valve will have a more free action and the core will be entirely removed from the 10 flushing action of the circulation water.

A particular advantage incident to the arrangement of the independent discharge chamber, resides in the suction action it produces on a core within the core barrel in 15 the event that the valve 11 for any reason fails to close tightly during the withdrawal of the drill. During such withdrawal, the vacuum influence created below the drill will have a tendency to draw the core out of the 20 core barrel, and in case the valve 11 does not close the core will be quite easily sucked from the core barrel, especially where the core is somewhat loose in the barrel.

Be reason of the arrangement of the discharge chamber and its discharge ports this 25 loss of the core is prevented, as the suction, acting through the ports 8, chamber 5, and improperly seated valve 11, will act on the top of the core, and in this manner counter- 30 act the suction influence on the bottom of the core, this counteraction effectively preventing a loss of the core.

With the construction illustrated the core 35 barrel and valve as a unit may be conveniently removed from the drill without disturbing the outer cutters or any of its other parts, also, the body member 3 carrying all the parts of the drill excepting the tubular body member 1, may be removed in a down- 40 ward direction from said body member 1 as a complete unit so the core barrel may be removed independently of the outer cutters.

The disc or closure 11 is not of larger diameter than the barrel 6 and thus enables 45 the barrel to be withdrawn through the lower end of the bit.

While the specific form of mechanism herein disclosed is well adapted to fulfil the objects primarily stated, it is to be understood 50 that I do not wish to limit the invention to the form of embodiment herein illustrated and described, for it is susceptible of embodiment in various other forms, all coming within the scope of the following claims.

55 I claim:

1. In a core drill, a body having a tubular shank providing a circulation water chamber, an imperforate tubular member carried by the body and extending upwardly 60 into the shank, said tubular member having a closed upper end and providing an independent discharge chamber, a centrally disposed core barrel carried by the body and extending upwardly into the discharge chamber, the body having independent dis- 65

charge ports communicating with the discharge chamber, a tubular core bit aligned with the core barrel, and outer boring cutters carried upon the lower end of the body.

2. In a core drill, a body having a tubular shank providing a circulation water chamber, an imperforate tubular member carried by the body and extending upwardly into the shank, said tubular member having a closed upper end and providing an independent discharge chamber, a centrally disposed core barrel carried by and extending through the body and upwardly into the discharge chamber, the body having independent discharge ports communicating with the discharge chamber, a tubular core bit carried by the lower end of the core barrel, and outer boring bits carried upon the lower end of the body.

3. In a core drill, a body having a tubular shank providing a circulation water chamber, an imperforate tubular member carried by the body and extending upwardly into the shank, said tubular member having a closed upper end and providing an independent discharge chamber, a centrally disposed core barrel carried by the body and extending upwardly into the discharge chamber, the bore of the body from the upper end of the body downwardly throughout a major portion of its length being larger than the diameter of the core barrel to provide an extension of the discharge chamber, and the body being provided with independent discharge ports communicating with said chamber extension, a tubular core bit aligned with the core barrel, and outer boring cutters carried upon the lower end of the body.

4. In a core drill, a body having a tubular shank providing a circulation water chamber, an imperforate tubular member carried by the body and extending upwardly into the shank, said tubular member having a closed upper end and providing an independent discharge chamber and the body having independent discharge ports communicating with the lower end of said discharge chamber, a centrally disposed core barrel carried by the body and extending upwardly into the discharge chamber, a check valve normally closing the upper end of the core barrel, a tubular core bit aligned with the core barrel, and outer boring cutters carried upon the lower end of the body.

5. In a core drill, a body having a central bore and provided with a tubular shank forming a circulation water chamber, a core barrel extending through said bore and secured to the body at its lower end with its upper end portion extending into the shank, a tubular core bit carried by the lower end of the core barrel, outer boring cutters carried by the body, and means for preventing communication between the circulation chamber and the upper end of the barrel.

6. In a core drill, a lower body member having an upwardly extending imperforate tubular member closed at its upper end and providing a discharge chamber, a centrally disposed core barrel carried by said body member and extending upwardly into the discharge chamber, a tubular core bit aligned with the core barrel, outer boring cutters carried by the body member, and a tubular shank detachably connected to the body member and surrounding the tubular member and forming therewith an annular circulation water chamber, the body having circulation ducts directing water from the water chamber to the cutters, and independent discharge ports communicating with the lower portion of the discharge chamber.
7. In a core drill, the combination of a drill string, a body attached to the lower end of the drill string and having a central bore and a tubular shank, outer cutters carried by the body, and a tubular core barrel having a tubular core bit at its lower end, the core barrel and said bore having screw threads connecting the same, said barrel extending upwardly into the shank and having a closure at its upper end of no larger diameter than the barrel, whereby the drill string may be removed from the well and the barrel and core bit removed as a unit from the drill string by pulling the core barrel downwardly and leaving the outer cutters in place.
8. In a core drill, a body having a tubular shank, a core barrel carried by the body and extending upwardly into the shank, a central core bit aligned with the core barrel, oppositely disposed boring cutters carried upon the lower end of the body with their cutting edges extending below its lower surface, the body being cut away on opposite sides to provide diametrically opposite substantially flat surfaces approximately radially disposed and extending upwardly from the lower surface of the body, said surfaces being provided with lateral dove-tail ways, the shanks of the cutters engaging said flat surfaces and having lateral dove-tail webs engaging in said ways, and means securing each cutter in place.
9. In a core drill, the combination of a body having a central bore and a tubular shank, outer cutters carried by the body, and a tubular core barrel having a closure of no larger diameter than the barrel at its upper end, and detachably secured to said bore at its lower end, said barrel with said closure being removable from the said bore in a downward direction, and extending upwardly into the shank, said core barrel being removable from the body independently of the outer cutters.
10. In a core drill, a body having a discharge chamber therein, a core barrel extending upwardly from the lower end of the drill into the discharge chamber and having a valve with a central guide stem, the space around the edge of the valve disc being unobstructed to permit water and core material to pass from the upper end of the core barrel into the discharge chamber and operating to maintain communication between the interior of the core barrel and the discharge chamber when the valve is slightly unseated, and means for maintaining communication from the discharge chamber to the exterior so that when the drill is pulled upwardly a partial vacuum will be formed in the discharge chamber as well as in the core barrel.
11. In a core drill, a body having a tubular shank providing a circulation water chamber, an imperforate discharge chamber disposed within the circulation chamber, a core barrel extending upwardly into the discharge chamber and having a valve at its upper end, a supporting member at the lower end of the body supporting the discharge chamber and the core barrel, said supporting member having openings therethrough communicating at the inner ends with the discharge chamber and inclining downwardly towards their outer ends whereby when the drill is pulled upwardly a partial vacuum will be formed in the discharge chamber as well as in the core barrel.

Signed at Los Angeles, California, this 4th day of August, 1922.

ROLAND R. CRUM.
